EX

OR D 1,059

E. J. Bridge, of Troy, N. Y.

Des. 1059

Letters Patent No. 1059, dated Dec. 2, 1858.

The schedule referred to in these Letters Patent and making part of the same.

To all whom it may concern:

Be it known that I, E. J. Bridge, of the City of Troy, in the County of Rensselaer, State of New York, have invented or produced a new and original design for plates of a Coal Cooking Stove called the Victory, and I do hereby declare that the following is a clear and exact description of the same, reference being had to the annexed drawings, making part of this specification, in which

Fig. 1. is an elevation of the Front plate.

Fig. 4. a section of the same.

Fig. 2. an elevation of the Side or jamb.

Fig. 5. is a section of the same.

Fig. 3. is a view of the Top plate, and

Fig. 6. a section of the same.

Fig. 7. is a section of the Corner of Front.

The description of the plates is as follows:

Figs. 1 & 4. front plate X is the feeding doors with (D) an ogee molding, with a cove forming the border of the doors (A), the panel formed with moldings radiating from the center of the doors (B) a flat band composed of segments of circles enclosing the ground work (C) which is a succession of angular grooves on which is the word Victory. (Z) is the bar or projection receiving the bottom of the feed doors (E) is an oval molding (F) a square or fillet of the Cove (G) H, is the corner the angles of which is ornamented with a beaded chamfer finished on the top and bottom with pointed arches. T is an opening for doors which are the same design as doors Y. (Fig. 2) Figs. 2 & 5. side or joint plate. Y is the door composed of (L) an ogee
